UNITED STATES PATENT OFFICE.

THOMAS A. MACAULAY, OF NEW YORK, N. Y.

MECHANICAL MOVEMENT.

SPECIFICATION forming part of Letters Patent No. 340,227, dated April 20, 1886.

Application filed February 2, 1886. Serial No. 190,628. (No model.)

To all whom it may concern:

Be it known that I, THOMAS A. MACAULAY, of the city, county, and State of New York, have invented a new and useful Improvement 5 in Mechanical Movements, of which the following, with the accompanying drawings, is a specification.

My invention relates to a mechanical movement in which a main rotary driving-shaft 10 rotates a supplementary shaft and vibrates a lever, as hereinafter more fully set forth, and pointed out in the claims.

In the drawings, Figure 1 is a side elevation. Fig. 2 is an end view, and Fig. 3 a modification of a part in detail.

A is the frame. B is a bed-plate. C is the main rotary driving-shaft, having a crank, D. E is a driving-wheel. F F² is a pitman-lever. G is a bell-crank lever suspended on centers 20 g g. H is a pitman-lever. I is a shaft having a crank, J, journaled in the bracket B². K is a horizontal lever, pivoted to the bed B by stud b. L is a stud pivoting the pitman-lever F F² to the short arm of the bell-crank 25 G. M is a stud pivoting the pitman-lever H to the extended arm G of the bell-crank lever. N is a cap hinged to the pitman-lever F by pin P, which connects the pitman-lever F F² to the crank D. O is a screw securing 30 the cap N to the pitman-lever. Q is a pin fixed to the pitman-lever F F², and engaging in a slot, a, in the pitman-lever H. S is a drag-link connecting the lower end of the pitman-lever H with the crank J. R is a ball 35 on the end of the long arm of the bell-crank lever G, engaging in the fork on the end of the horizontal lever K.

Motion being imparted to the main shaft C, a vertical and vibratory motion is caused in 40 the pitman-lever F F², and a vibratory motion is imparted to the bell-crank lever G, and a vertical and vibratory motion is imparted to the pitman-lever H by reason of its connection to the bell-crank G at M, and by reason of its 45 connection with the pitman-lever F F² by pin Q in the slot a. This vertical and lateral motion of the pitman-lever H imparts a rotary motion to the crank J through the drag-links S.

It will be observed that the point M travels 50 a greater distance than the point L, by reason of its greater distance from the center of the lever G. It therefore lifts the pitman-lever

H a corresponding distance, and the pitman-lever H being longer from the center of M to the center of S² than the pitman-lever F F² is 55 from the center of its connection with the crank D to the center of its connection to the bell-crank G, it results that the vibratory movement of the pitman-lever H at its lower end is greater than if the distance from D to L and from M to S² were equal. Therefore the vertical and vibratory movements of the pitman-lever H are increased, and a crank of greater throw or longer leverage can be used 60 on the shaft I than if its rotary movement were obtained by a direct connection of the pitman-lever F F² with the crank J. By this means 65 a greater power can be exerted by the crank I and an easier movement obtained, as well as smoothness and ease in action.

It will be readily seen that instead of giving the lever H its vibratory movement from the pitman-lever F F² it may be extended, as shown in Fig. 3, forked, and connected to the crank D, the crank D being extended sufficiently.

It will be readily seen that instead of the pin Q and slot a an ordinary connecting-link may be substituted. It will also be readily understood that a common stud may be used 80 to connect the pitman-lever F F² and the pitman-lever H H² to the arm G.

The above-described mechanical movement is useful in sewing-machines and for other purposes.

Having described my invention, I claim—

1. A mechanical movement consisting of a main rotary shaft having a crank, as D, a primary pitman-lever, as F F², operatively connected with a primary vibrating lever, as G G², 90 a horizontal lever, as K, a secondary pitman-lever, as H, pivoted to an arm of said primary lever, and connected by suitable devices with said primary pitman-lever, to cause a lateral motion therein, and a shaft, as I, suitably connected with said pitman-lever H, to impart a rotary motion to said shaft I, as and for the purpose specified.

2. A mechanical movement consisting of a main rotary shaft having a crank, as D, a pitman, as F, operatively connected with a primary vibrating lever, as G G², a horizontal lever, as K, a pitman-lever, as H H², suitably connected, to cause a lateral movement there-

in, and a shaft, as I, suitably connected with said pitman-lever, to impart a rotary motion to said shaft I, as and for the purpose set forth.

- 5 3. A mechanical movement consisting of a main rotary shaft having a crank, as D, a pitman, as F, operatively connected with an arm, as G, a pitman-lever pivoted to said arm G, and connected by suitable devices to impart 10 to it a vibratory movement, and a shaft, as I, suitably connected with said pitman-lever, to cause a rotation in said shaft, as and for the purpose set forth.
4. A mechanical movement consisting of a

main rotary shaft having a crank, as D, a primary pitman-lever, as F F², operatively connected with an arm, as G, a secondary pitman-lever, as H, pivoted to said arm G, and suitably connected with said primary pitman-lever F F², to impart to it a lateral motion, and 15 a shaft, as I, suitably connected with said secondary pitman-lever, to cause said shaft I to rotate, as and for the purpose specified.

THOS. A. MACAULAY.
